UNITED STATES PATENT OFFICE

2,594,251

SAFETY MECHANISM FOR SPLICING MACHINES

James Trathen, Cuyahoga Falls, Ohio, assignor to The B. F. Goodrich Company, New York, N. Y., a corporation of New York

Application February 4, 1950, Serial No. 142,443

5 Claims. (Cl. 154—9)

1

This invention relates to safety mechanisms for splicing machines and is particularly useful in providing for safe operation of tube splicing machines.

Heretofore, the splicing of inner tubes before vulcanization thereof has been accomplished generally by use of splicing machines of the type shown and described in the patents to Haase No. 2,024,577, Haase No. 2,024,578, and Campbell No. 2,273,464. In such an apparatus the tube ends are opposed to each other, are clamped in flattened condition and facing each other, the opposed ends are trimmed by reciprocating knife means and the cut ends are moved laterally toward and into pressed engagement with one another to provide a butt splice. Such machines operate through a cycle of movements controlled by a timer having a cam shaft. Stopping rotation of the cam shaft has depended upon a stop latch but it has been found that in use the stop latch often fails to function properly and consequently the cycle of operation has been repeated, endangering the hands of the operator who must adjust the tube ends beneath the clamping and cutting members.

The present invention aims to overcome the foregoing and other difficulties.

Objects of the invention are to provide for positive locking the clamping members in their raised position, to provide for positively preventing repetition of cycle movement, to provide dual locking mechanism requiring use by both hands for unlocking and to combine the locking means with the electrical control means so that the splicing machine cannot be started with the locking means engaged.

These and other objects will appear from the accompanying drawings.

Of the drawings,

Fig. 1 is a side elevation of apparatus corresponding to and embodying the invention in engaged position attached to a splicing machine, the splicing machine being shown in dot-and-dash lines,

Fig. 2 is a front elevation thereof, and

Fig. 3 is a view similar to Fig. 1 showing the apparatus in disengaged position.

Referring to the drawings, which show a machine constructed in accordance with and embodying the invention, the numeral 10 designates the frame of a tube splicing machine having thereon spaced-apart aligned supports 11, 12 for supporting tube ends 13, 14. These supports are moved laterally as seen in Fig. 2, toward and from each other. Clamp members 15, 16 are pivotally mounted one on each support as at 17 for movement toward and from the supports 11, 12 to clamp the tube ends thereagainst. The clamp members are operated by fluid operated cylinders such as 18 controlled by timing mecha-

2

nism (not shown). The timer is set in operation by a pair of limit switches 19, 20 connected in series and adapted to be closed manually, the two switches requiring use of both of the operator's hands for closing them.

To provide positive locking of the clamps 15, 16 in their raised position, each clamp is provided with an ear 21 having a locking pin 22 projecting laterally therefrom. A swinging latch bar such as 23, 23' is pivotally secured as at 24 to the frame 10 above each clamp member, and has a notch 26 for engaging the locking pin 22. The notches 26 are open toward the frame to permit swinging of the latch bars away from the frame 10 to release the pins. As the clamps 15, 16 move laterally with the supports 11, 12, the pins 22 may enter the slots 26 of the bars 23, 23' when the clamps are in the raised position illustrated and the supports 11, 12 are moved apart at the end of the splicing cycle of movements. To restrain the latch bars from lateral movement, guides 27, 28 are fixed to frame 10 and have slots for confining the latch bars from moving laterally as seen in Fig. 2 but permit 25 swinging movement thereof as seen in Fig. 1.

For swinging the latch bars outwardly from frame 10 and simultaneously closing switches 19, 20, a pair of levers 30, 31 are pivotally supported from brackets 32, 33 fixed to frame 10. Each lever 30, 31 has a link 34 pivotally connected to it. The links each engage a crank arm 35 or 36. The crank arms are fixed respectively to horizontal shafts 37, 38 rotatable in bearings 39, 40 secured to frame 10. Shafts 37, 38 have arms 41, 42 fixed to their opposite ends respectively. Pins 43, 44 are secured to the latch bar 23, 23' in position to be engaged by arms 41, 42 when levers 30, 31 are swung to the left in Fig. 1 and thereby to unlatch the clamps 15, 16. Links 45, 46 pivotally connect latch bars 23', 23 respectively to the arms of switches 19, 20 and close these switches at the same time.

The operation is as follows: With the clamps 15, 16 raised, the latch bars are hooked to the clamps and prevent their being lowered while the operator places the ends of the tube over the supports 11, 12. The operator then grasps levers 30, 31, one with each hand, and pulls them forward. This unlatches the clamps and closes switches 19, 20 to start the timer. The timer then lowers the clamps 15, 16 and causes the machine to trim the ends of the tube, moves supports 11, 12 toward each other, and splices the tube, thereafter raising the clamps 15, 16 and then moving supports 11, 12 apart. As the supports move apart, pins 22 enter the slots 26 of the latch bars from the sides thereof and this ends the normal cycle of the machine. Should the machine attempt to repeat its cycle, the

latch bars prevent lowering the clamps until the operator again pulls levers 23, 23' forward.

The latch bars positively prevent lowering of the clamps upon the operator's hands while the operator is placing the ends of the tube to be spliced in place and the clamps cannot be moved from their raised position until both hands of the operator are on the levers 23, 23'.

While the apparatus has been described as used on tube splicers, it may also be used on tread splicers or similar machines.

Variations may be made without departing from the scope of the invention as it is defined by the following claims.

I claim:

1. Safety mechanism for splicing machines of the type having a frame and a work clamp mounted thereon for relative movement laterally of said frame and also along said frame in a direction across the path of its lateral movement together with operating mechanism therefor, said safety mechanism comprising a latch bar mounted on said frame for movement relative thereto across the path of lateral movement of said work clamp, said latch bar having a notch open in one direction of the plane of movement of said latch bar, a pin on said clamp engageable in said notch from the side of said bar by lateral movement of said clamp in one direction to lock said clamp against clamping movement until release of said latch bar, and means for disengaging said latch bar from said clamp by movement of the latch bar in a direction across the path of lateral movement of said clamp.

2. Safety mechanism for splicing machines of the type having a frame and a pair of work clamps mounted thereon for relative movement laterally of said frame toward and from each other and also movement in a direction across the path of their lateral movement together with operating mechanism therefor, said safety mechanism comprising latch bars mounted on said frame for movement relative thereto across the path of lateral movement of said work clamps, each latch bar having a notch open in one direction of the plane of movement of said latch bar, a pin on each said clamp engageable in a notch of a latch bar from the side of said bar by lateral separating movement of said clamps to lock said clamps against clamping movement until release of said latch bar, and means individual to each latch bar for disengaging the latch bar from its clamp by movement of the latch bar in a direction across the path of lateral movement of said clamp.

3. Safety mechanism for splicing machines of the type having a frame and a work clamp mounted thereon for relative movement laterally of said frame and also along said frame in a direction across the path of its lateral movement and operating mechanism controlling movement of said clamp through a cycle of movements, said safety mechanism comprising a latch bar mounted on said frame for movement relative thereto across the path of lateral movement of said work clamp, said latch bar having a notch open in one direction of the plane of movement of said latch bar, a pin on said clamp engageable in said notch from the side of said bar by lateral movement of said clamp in one direction to lock said clamp against clamping movement until release of said latch bar, control means for initiating the cycle of movement of the machine including a control member operable by movement of the latch bar relative to said frame across the path of lateral movement of said work clamp, and means for so

moving the latch bar to disengage it from said clamp and to start the cycle of operation.

4. Safety mechanism for splicing machines of the type having a frame and a pair of work clamps mounted thereon for relative movement laterally of said frame toward and from each other and also movement in a direction across the path of their lateral movement together with operating mechanism controlling movements of said clamp through a cycle of movements, said safety mechanism comprising latch bars mounted on said frame for movement relative thereto across the path of lateral movement of said work clamps, each latch bar having a notch open in one direction of the plane of movement of said latch bar, a pin on each said clamp engageable in a notch of a latch bar from the side of said bar by lateral separating movement of said clamps to lock said clamps against clamping movement until release of said latch bar, control means for initiating the cycle of movement of the machine including a plurality of control members each operable by movement of a latch bar relative to said frame across the path of lateral movement of said work clamps to collectively start the cycle of movement of the machine, and means for so moving the latch bars to disengage them from said clamps and to start the cycle of operation.

5. Safety mechanism for splicing machines of the type having a frame, a pair of spaced work clamps thereon and means for moving the clamps simultaneously into clamping relation with the frame, said safety mechanism comprising a latch bar mounted for arcuate movement adjacent each clamp, means for releasably engaging each latch bar with its respective clamp when the clamps are out of clamping position whereby the latch bars maintain the clamps against said movement thereof, a pair of handles pivotally secured to the frame at points remote from each other and remote from the work clamps, means connecting one of said handles to one of said latch bars and other similar means connecting the other of said handles to the other of said latch bars, each of said connecting means being operable only upon simultaneous pivotal movement of the handles to move said latch bars arcuately, thereby releasing the engaging means between the latch bars and their respective work clamps, and actuating means also operable only by said simultaneous movement of the handles to energize said clamp-moving means to effect the movement of the clamps into clamping relation with the frame.
